UNITED STATES PATENT OFFICE.

JOHN T. LANCASTER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

PULLING-OVER MACHINE.

1,333,537.

Specification of Letters Patent.

Patented Mar. 9, 1920.

Application filed March 2, 1915. Serial No. 11,539.

To all whom it may concern:

Be it known that I, JOHN T. LANCASTER, a citizen of the United States, residing at Beverly, in the county of Essex and State 5 of Massachusetts, have invented certain Improvements in Pulling-Over Machines, of which the following description, in connection with the accompanying drawings, is a specification, like reference characters on 10 the drawings indicating like parts in the several figures.

This invention relates to machines for use in the manufacture of shoes and particularly to upper pulling machines, and is 15 herein shown as embodied in a machine having means for pulling an upper over a last at the toe and at opposite sides of the forepart of the last.

In machines of a well known type as previously 20 constructed the toe gripper is yieldingly connected with power operating mechanism by which it, in company with side grippers, seizes the upper and pulls it and then comes to rest holding the upper under 25 tension for inspection and adjustment. When the machine is restarted the toe gripper, again in company with and in predetermined time relation to the side grippers, is made by the power mechanism to over- 30 draw the upper into position for the wiping and fastening mechanism to take control of the upper and secure it to the shoe sole or innersole. There is opportunity for independent movement of the toe gripper while 35 the machine is at rest holding the upper under tension but such movement must be manually effected by reaching up to a handle on the front end of the updraw lever. That handle must be further elevated to increase 40 the tension on the upper and it must be pulled down to relax the tension. There is no means to secure the toe gripper in the position to which it is manually moved. All of the power driven upper pulling movements 45 of the toe gripper are yieldingly effected through a spring which must be weak enough to insure against overstraining or tearing the uppers.

The present invention has for an object 50 to provide improved means for operating grippers and, in one aspect, particularly for operating the toe gripper of a pulling-

over machine. An important feature of this invention consists in the combination with a toe gripper of a pulling-over machine and power operating mechanism therefor of 55 manually controlled means by which the power mechanism may be made to operate the toe gripper as desired. In the embodiment of the invention herein shown, said 60 means is constructed and arranged to cause said mechanism to move the toe gripper either in the direction to tension the upper or in the direction to relax tension previously applied. Also in the construction 65 shown the power mechanism may be made to open the toe gripper independently of the normal operation of the machine and the gripper may, if desired, be made by said mechanism to reengage the upper at such 70 other point as may be required. Another feature of this invention consists in means to cause power mechanism to operate the toe gripper of a pulling-over machine independently of the side grippers. The illustrated embodiment of the invention provides 75 means for causing the power mechanism to move the toe gripper either upwardly or downwardly without disturbing the side grippers. 80

A further feature of this invention, as embodied in a pulling-over machine comprising a toe gripper and upper fastening means and power mechanism connected with the gripper and fastening means and having a normal cycle in which it causes the gripper to pull the upper and the fastening means to fasten it, consists in the provision of manually controlled means which may be used at the will of the operator to cause the power mechanism to change the tension of the portion of the upper held by the toe gripper. 85

In still another aspect the invention provides novel means whereby the toe gripper and the side grippers of a pulling-over machine may be moved at the will of the operator to vary as desired the tension of the upper both longitudinally and transversely 90 of the last. 100

These and other features of the invention including certain details of construction and combinations of parts will now be described with the aid of the accompanying drawings,

which show an illustrative embodiment of the invention, and will then be pointed out in the claims.

Figure 1 of the drawings is a side elevation of a pulling-over machine of the type shown and fully described in United States Letters Patent No. 1,029,387, granted June 11, 1912, on application of Ronald F. McFeely, and equipped with this invention, 10 and

Fig. 2 is a perspective view, on a larger scale than Fig. 1, of some of the important parts of the machine provided by this invention.

15 The general organization and operation of the machine and its construction and arrangement except in the particulars herein-after discussed is like that of the machine of said McFeely Patent No. 1,029,387, and 20 need not be here described except in so far as may be needed to make clear an understanding of this present invention and the way in which it is embodied in that machine.

25 The base shaft 1 in Fig. 1 carries a large pinion 2 formed on a constantly running pulley. The pinion 2 drives continuously a gear 4, Fig. 1, located at the left hand side of the vertical median plane of the machine 30 and associated with the toe gripper and the left hand side gripper as will be described. On the right hand side of said vertical median plane is a similar gear and connections therefrom to the side gripper on that side 35 of the machine, said connections being duplicates of those which will be described for the left hand side of the machine and therefore requiring no explanation.

The gear 4 is fast on a short shaft carrying 40 a worm 6 which engages a worm gear 8 and thereby drives a vertical shaft 10. The vertical shaft carries on its upper end a worm 12 engaging a worm gear 14 by which a shaft 16 extending longitudinally of the 45 machine is continuously rotated in bearings formed for it in a bracket attached to the side of the machine.

The continuously rotated longitudinal shaft 16 has on its front end a worm 100, 50 Figs. 1 and 2, engaging a worm gear 102 on a short vertical shaft 106 which is therefore continuously driven. The shaft 106 has on its head a beveled gear 108 which is located between and adapted to have driving engagement with both of two beveled gears 110 and 112 which are loose on a transverse shaft 114.

The shaft 114 has fastened on it a pinion 116 which meshes with a larger pinion 60 118 that is engaged by a segmental rack on the lower end of a lever 120, Figs. 1 and 2. Lever 120 is fulcrumed on a plate 122 rigidly attached to the machine frame for that purpose, see Fig. 1, and the hub of the lever 65 has gear teeth by which it has driving en-

gagement with a segmental gear 123 that is fastened to the toe gripper updraw lever 124 pivoted on fulcrum rod 146.

The updraw lever 124 supports, near its front end, the toe gripper 125 and at its rear end said lever is connected through an adjustably tensioned spring 126 with a slide 127 which carries a roll standing in a track in a cam block 128 on the cam shaft 55 which is driven at times by a pulley 129 belted to a pulley 131 on the base shaft 1, there being a treadle controlled clutch between the pulley 131 and the constantly running pulley carrying pinion 2. The side grippers 47 are suspended from updraw 80 levers 45, fulcrumed on rod 146 and connected through adjustably tensioned springs 48 with a slide 49 having a roll standing in a cam track in the front face of the brake cam 50 on shaft 55 by which the machine 85 is stopped automatically with the upper under tension and again at the end of the cycle of the machine. This updraw mechanism is the same as that employed in the machine of said McFeely patent and constitutes pulling-over means and power operated mechanism therefor having a normal cycle of movements and arranged to cause the grippers to seize the upper and come to rest with the upper under tension 90 for inspection and adjustment, as explained in said patent. There is also associated with each gripper a tacker which is operated by said power mechanism to fasten the pulled over upper when the machine is restarted. 95 The machine can be operated to pull over shoes precisely as provided for in said McFeely patent and independently of the new mechanism which is provided by this invention if so desired.

105 The new mechanism connected with the toe gripper updraw lever is manually controlled by a hand lever 130 fulcrumed on a stud 132, Fig. 2, and connected to the inner end of shaft 114 to slide said shaft and the pinion 116 endwise. The pinion has on each end a ratchet face adapted to clutch with a similar ratchet face on the adjacent end of one or the other of the continuously driven beveled gears 110, 112 which run in opposite directions on the shaft 114 and are free on said shaft except when they are clutched to it by the pinion 116. The pinion is wide enough to maintain driving engagement with pinion 118 in all positions and when it is clutched to the beveled gear 110 it will be turned in the direction of the arrow on the hub of that gear and will rotate pinion 118 in the direction to swing lever 120 rearwardly and through segment gear 123 will raise the gripper carrying end of updraw lever 124. The hand lever 130 and connections constitute the illustrated embodiment of means under control of the operator for causing the power mechanism, 130

operating through pinion 2 and connections to shaft 114 and updraw lever 124, to increase or decrease the tension under which the toe gripper holds the upper. In practice the updraw spring 126 may be adjusted to a tension which will be only sufficient to pull up the upper lightly and straighten it on the last, after which the final pull, and it may be the chief upper stretching, will be effected by use of the said means under control of the operator to cause the power mechanism to increase the tension. The initial pull is a yielding one the extent of which may be measured in units of force. The second pull is unyielding and may be measured in units of length, and it is entirely under control of the operator. The final and most critical portion of the upper stretching operation may thus be effected in such manner that the operator is afforded the opportunity to observe carefully the condition of the stock and to stop the upper tensioning operation when the condition of the stock and the position of the tip seam indicate that no further pulling is desirable. To facilitate manual control the clutch faces on the pinion 116 and the gears 112, 110 are backwardly faced ratchet teeth adapted to slip past each other whenever the resistance to movement of the toe gripper exceeds the force with which the operator is pressing the hand lever 130.

A common practice of many operators is to set the toe gripper spring 126 to cause a strong pull to be applied by that gripper longitudinally of the upper to pull the upper forwardly on the last, and during the period of rest the operator reaches up to the toe gripper lever and manually relieves the longitudinal tension so that the side grippers can better pull the upper transversely of the last down to the wood between the toe and the instep of the last. When a machine is equipped with the illustrated embodiment of this invention the same result can be accomplished much easier and more expeditiously by swinging the hand lever 130 toward the left, Fig. 2, and causing the power mechanism, through beveled gear 112 and pinion 118, to lower the toe gripper and decrease the longitudinal tension on the upper.

If it is observed, after the final pull on the upper, that successful results in the subsequent over-drawing of the upper into position to be secured to the innersole require that the toe gripper engage the upper at a different distance from the edge, this gripper may be lowered by power under control of the lever 130 far enough to cause its jaws to be opened by the automatic means characteristic of the illustrative type of machine and more fully shown and described in United States Letters Patent No. 1,030,264, granted on June 18, 1912, upon the application of R. E. McFeely. The upper may

then be readjusted in the gripper, after which, by the further manipulation of the lever 130, the gripper may be caused to close again upon the upper and to pull it to the precise extent desired.

For causing the toe gripper to maintain the position to which it is moved by the use of the described manual control of the power mechanism the shaft 114 has on its outer end, Fig. 2, two peripheral series of oppositely faced ratchet teeth with which co-operate opposed pawls 140, 142 held to their work by springs 141, 143. The ratchet teeth of both series run out to a smooth peripheral surface located between them and which, in the central position of the endwise movable shaft and the hand lever 130, holds both pawls out of touch with the ratchet teeth.

The use of the present invention on a pulling-over machine of the type shown in the said prior patent is very advantageous, as will be understood from the explanation which has been given. Further advantages are obtained by the use in that machine of additional manually controlled means for causing the power mechanism to increase or decrease the tension applied by the side grippers, and manually controlled means for this purpose which is adapted for use in cooperation with the above described mechanism will therefore be briefly described and reference may be had to application Ser. No. 843,865 by myself and another inventor for a fuller description and illustration of the same.

The shaft 16 carries a driven clutch member 18 controlled by a hand lever 30 by which it can be made to drive one or the other of two beveled gears 24, 25 for turning in one direction or the other a beveled gear 32 fast on the lower end of a short vertical shaft the upper end of which is a screw 35 operating in a block 36 having connection through slide 38 and fork 41, 42 with the rear end of the left hand side gripper lever 45. The hand lever 30, clutch member 18 and screw 35 constitute manually controlled means by which the power operating mechanism can be made to raise and lower the left hand side gripper. Duplicate means is provided on the other side of the machine to raise and lower the other side gripper, and the adjacent ends of the hand levers 30 for said side grippers are arranged in such proximity that they can, if desired, be manipulated simultaneously by the same hand of the operator while he employs his other hand to manipulate the hand lever 130, whereby the toe and side grippers will all be responsive to simultaneous manual control.

A brake 145 arranged to engage the shaft 114 serves to hold the shaft adjusted endwise in either direction with locking pawl 140, or 142 in engagement with its ratchet teeth to lock the toe gripper up or down.

The brake readily allows the shaft to be moved endwise by lever 130 to central position to cause the tapered ends of the ratchet teeth to force the pawl 140, or 142, whichever is operative, up on to the smooth peripheral portion of the shaft between the teeth, in which position the teeth offer no resistance to the return of the toe gripper to its normal position.

10 For restoring the hand lever 130 to its normal position without attention from the operator after each use, and thereby shifting shaft 114 endwise to disengage the holding pawls from their ratchets, an arm 74 is fulcrumed at 73 and has a connection, not shown, with the brake rod 76 by which the arm 74 is swung upwardly when the brake is released and the machine started for tacking the upper. A link 150 extends from arm 74 20 forwardly and upwardly to a swinging cam 152, pivoted at 154, and having a tapering guideway, Fig. 2, for a roll 155 that depends from the hand lever 130. When the cam 152 is swung forwardly one or the other wall of 25 the guideway will engage the roll and wedge it and hand lever 130 to central position. The arm 74 has also a tapering recess in its upper face the walls of which are adapted to engage a roll 72 on the hand lever 30 and re-store said lever and the parts controlled by it 30 to normal position when the machine is restarted for operating the tackers. A similarly formed and operated arm 74 at the opposite side of the machine simultaneously re-stores the right hand lever 30 to normal position when the machine is restarted. The toe tacker is shown at 156 and one of the side tackers at 157 in Fig. 1.

Having explained the nature of this invention and described an illustrative machine embodying the same in the best form now known to me, I claim as new and desire to secure by Letters Patent of the United States:

45 1. A pulling-over machine having, in combination, toe and side grippers, constantly driven power operating mechanism, and means under control of the operator for connecting said power operating mechanism to the toe gripper alone to move the toe gripper without moving the side grippers from the 50 positions which they occupy at the beginning of such movement of the toe gripper.

55 2. A pulling-over machine having, in combination, toe and side grippers, constantly driven power operating mechanism, and means under control of the operator constructed and arranged to connect said power operating mechanism to the toe gripper alone to impart to the toe gripper an upper 60 pulling movement independent of the movements of the side grippers.

65 3. A pulling-over machine having, in combination, toe and side grippers, power operating mechanism having operative connec-

tions with the toe and side grippers for causing them to pull a shoe upper, and manually controlled means by which the power operating mechanism can be made to move the toe gripper independently of the side grippers to relax the pull on the portion of upper held by the toe gripper.

4. A pulling-over machine having, in combination, toe and side grippers, power operating mechanism, connections between said mechanism and the toe and side grippers for causing them to pull a shoe upper and come to rest holding the upper under tension longitudinally and transversely of the shoe, and manually controlled means for causing the power operating mechanism to change the tension on the upper effected by the toe gripper without similarly changing the tension in the direction in which the side grippers are pulling the upper.

5. A pulling-over machine having, in combination, toe and side grippers, power operating mechanism, connections between said mechanism and the toe and side grippers for causing them to pull a shoe upper and come to rest holding the upper yieldingly under tension, and manually controlled means for causing the power operating mechanism positively to move the toe gripper alone in a direction to change the tension.

6. A pulling-over machine having, in combination, toe and side grippers, power operating mechanism, means connecting said mechanism yieldingly with the toe gripper 100 to impart upper pulling movements to said gripper, and means under control of the operator for causing said mechanism to impart an unyielding upper pulling movement to the toe gripper.

7. A pulling-over machine having, in combination, toe and side grippers, power operating mechanism, means connecting said mechanism yieldingly with the toe gripper to impart upper pulling movement to said gripper and come to rest with the gripper holding the upper under tension, and means under control of the operator by which said mechanism may be caused to move the toe gripper unyieldingly either to increase or to 110 relax the tension.

8. A pulling-over machine having, in combination, toe and side grippers, power operating mechanism, means connecting said mechanism with the toe gripper to impart 120 upper pulling movements to said gripper, and means under control of the operator for causing said mechanism to open the toe gripper independently of the side grippers.

9. A pulling-over machine having, in combination, toe and side grippers, power operating mechanism and connections thereto for giving normal movements to the toe gripper, and manually controlled means by which the power operating mechanism may be 130

made to give to the toe gripper alone movement additional to its normal movements.

10. A pulling-over machine having, in combination, toe and side grippers, power operated mechanism connected with the toe gripper to impart upper pulling movements to said gripper, and means under control of the operator for causing said mechanism to open the toe gripper alone and to reengage it with the upper.

11. A pulling-over machine having, in combination, toe and side grippers, power operating mechanism and connections to the toe and side grippers to effect pulling of the upper, and means under control of the operator for causing said mechanism to operate the toe gripper for increasing or for relaxing the tension of the upper independently of the side grippers.

20. 12. A pulling-over machine having, in combination, a toe gripper, a toe tacker, power operating mechanism and connections to the gripper and the tacker and having a normal cycle of operation in which the gripper is caused to pull the upper and the tacker to fasten the upper, and manually controlled means which may be used at the will of the operator to cause the power operating mechanism to effect additional movements of the toe gripper alone.

30. 13. A pulling-over machine having, in combination, a toe gripper, a toe tacker, power operating mechanism and connections to the gripper and the tacker and having a normal cycle of operation in which the gripper is caused to pull the upper and the tacker to fasten the upper, and manually controlled means which may be used at the will of the operator to cause the power operating mechanism to effect release of the upper by the toe gripper alone prior to the normal time for such release in the cycle of the machine's operation.

40. 14. A pulling-over machine having, in combination, a toe gripper, side grippers, power operated mechanism for updrawing said grippers, and means under control of the operator as he stands in working position for causing said mechanism to increase or decrease the updraw of the toe gripper independently of the side grippers.

50. 15. A pulling-over machine having, in combination, a toe gripper, side grippers, a last rest, power operated mechanism for moving said grippers and the last rest relatively to stretch an upper longitudinally and transversely, and means under control of the operator as he stands in working position for causing said power operated mechanism to increase or decrease the stretching produced by the relative movement of the last rest and the toe gripper, without affecting the stretching produced by the relative movement of said rest and the side grippers.

16. A pulling-over machine having, in combination, a toe gripper, side grippers, power operated mechanism for moving said grippers to pull an upper longitudinally and transversely, and means under control of the operator by which said mechanism can be caused further to pull the upper either longitudinally or transversely.

17. A pulling-over machine having, in combination, a toe gripper, side grippers, mechanism for moving said grippers to pull an upper longitudinally and transversely, and power driven mechanism under control of the operator by which to increase or decrease either the longitudinal or the transverse pull upon the upper.

18. A pulling-over machine having, in combination, pulling-over means including a toe gripper, upper fastening means, power operated mechanism constructed and arranged to cause the pulling-over means to come to rest with the toe gripper holding the upper under tension for inspection and to cause the fastening means to fasten the upper when the machine is restarted, and means by which the toe gripper can be caused to change the tension on the upper and is locked to hold the upper under the changed tension for the operation of the fastening means.

95. 19. A pulling-over machine having, in combination, pulling-over means including a toe gripper, upper fastening means, power operated mechanism constructed and arranged to cause the pulling-over means to come to rest with the toe gripper holding the upper under tension for inspection and to cause the fastening means to fasten the upper when the machine is restarted, and means by which the power operated mechanism can be made to increase or decrease the tension on the upper held by the toe gripper and maintain the changed tension for the operation of the fastening means.

100. 20. A pulling-over machine having, in combination, pulling-over means for stretching an upper transversely and longitudinally of a last including a toe gripper, mechanism for imparting normal movements to the gripper, and manually controlled power operated mechanism by which to impart other movements to the toe gripper independently of the remainder of the pulling-over means.

110. 21. A pulling-over machine having, in combination, a gripper, means by which the gripper can be moved, and means for locking the gripper against return movement comprising an endwise movable shaft connected with the gripper to be rotated when the gripper is moved and having two peripheral series of oppositely faced ratchet teeth separated by an untoothed peripheral face, and oppositely faced locking pawls constructed and arranged relatively to the

ratchet teeth to coöperate alternatively with the respective series of ratchet teeth when the shaft is displaced endwise in one direction or the other and to engage the un-toothed peripheral face when the shaft is in its central longitudinal position.

22. A pulling-over machine having, in combination, toe and side grippers, power operating mechanism, and means to connect 10 said power operating mechanism to the toe gripper alone to operate the toe gripper independently of the side grippers.

23. A pulling-over machine having, in combination a plurality of upper pulling devices including a toe gripper, power operated mechanism for actuating said devices, and means under the control of the operator for applying said power operated mechanism to the toe gripper alone.

24. A machine for fitting uppers to lasts having, in combination, means adapted to engage the forepart of the upper and pull the upper longitudinally of a last, and power operated means arranged to cause the 25 pulling means to pull the upper in a direction lengthwise of the last only and hold it under tension and, at the will of the operator, to relieve the pull in said direction and allow the upper to slack back to a limited extent.

25. A machine for fitting upper to lasts having, in combination, means to pull an upper lengthwise of a last down the instep incline of the last and hold the upper under tension while the upper at the sides of the ball is pulled transversely of the last, and power mechanism under control of the operator for moving reversely the pulling means to allow the upper to slack back 40 toward the instep incline of the last after the upper has been pulled transversely at the ball of the last while maintaining the tension applied by the pulling means acting transversely of the last.

26. A pulling-over machine having, in combination, grippers for engaging an upper on a last, power operating mechanism for effecting relative movement of the last and said grippers to tension the upper both 50 longitudinally and transversely of the last, and manually controlled means for making operative connection with said power operating mechanism to cause said mechanism to change the tension of the upper longitudinally of the last without affecting the transverse tension.

27. A pulling-over machine having, in combination, toe and side grippers for engaging an upper on a last, power operated 60 mechanism for effecting relative movement of the last and said grippers to tension the upper over the last, and manually controlled means for connecting the toe gripper to said power operated mechanism to cause the 65 toe gripper alone to be moved to vary the

tension of the upper longitudinally of the last.

28. A pulling-over machine having, in combination, toe and side grippers, power operated mechanism connected to said grippers to cause them to pull an upper over a last, and additional connections between said power operated mechanism and the toe gripper and side grippers arranged for separate manual control to permit the tension of 75 the upper longitudinally and transversely of the last to be varied independently at the will of the operator.

29. A pulling-over machine having, in combination, toe and side grippers, power operated means connected to said grippers to cause them to pull an upper over a last, supplemental power driven mechanisms for effecting additional movements of the toe and side grippers independently of each other, and a manually operated controlling member for each of said mechanisms to render it effective to move its connected gripper.

30. A pulling-over machine having, in combination, a toe gripper, side grippers, power operated mechanism connected to said grippers for imparting upper pulling movements thereto, supplemental manually controlled means for causing said power operated mechanism to effect a subsequent movement of the toe gripper to change the tension of the upper longitudinally of the last, means for locking the toe gripper in the position to which it is moved by said supplemental means, and power driven means for unlocking the toe gripper to permit it to return to its initial position.

31. A pulling over machine having, in combination, a toe gripper, side grippers, mechanism for causing said grippers to seize an upper, and means under control of the operator by which the toe gripper and the side grippers may be made independently to pull the upper.

32. A machine of the class described having, in combination, grippers for engaging an upper at the toe and at opposite sides of a last, power driven operating mechanism, connections to said mechanism for effecting 115 relative movement of said grippers and the last to pull the upper, and means for enabling the operator to render said mechanism effective subsequently to cause independent movements of the toe gripper and the side 120 grippers for changing the relative tension of the upper longitudinally and transversely of the last.

33. A machine of the class described having, in combination grippers for engaging 125 an upper at the toe and at opposite sides of a last, constantly driven power operating mechanism, means for causing said mechanism to effect a relative movement of the grippers and the last to pull the upper, and 130

means for rendering said mechanism effective subsequently to move the toe gripper independently of the side grippers in a direction to change the tension of the upper 5 lengthwise of the last.

34. A machine of the class described having, in combination, grippers for engaging an upper at the toe and at opposite sides of a last, power operating mechanism, connections between said mechanism and the grippers for operating said grippers to pull the upper, and additional connections between said mechanism and the toe gripper arranged for manual control to render said mechanism 10 effective subsequently to move the toe gripper at the will of the operator in a direction to change the tension of the upper without similarly moving the side grippers.

35. A machine of the class described having, in combination, grippers for engaging an upper at the toe and at opposite sides of a last, power operated means for effecting relative movement of the last and said grippers to pull the upper, and power operated means 20 subject to manual control for subsequently moving the toe gripper alone a distance determined by the operator for changing the tension of the upper.

36. A machine of the class described having, in combination, grippers for engaging an upper at the toe and at opposite sides of a last, means for moving said toe and side grippers to pull the upper, connections to the toe gripper normally idle during said movement of the grippers, and means for subsequently applying power through said connections to move the toe gripper independently of the side grippers in a direction to change the tension of the upper.

40 37. A machine of the class described having, in combination, grippers for engaging an upper at the toe and at opposite sides of a last, means for effecting relative movement of the last and said grippers to pull the 45 upper, and power operated connections to the toe gripper for subsequently effecting a movement of the toe gripper independently of the side grippers in a direction to change the tension of the upper.

50 38. A machine of the class described having, in combination, grippers for engaging an upper at the toe and at opposite sides of a last, mechanism having a prescribed range of movement for operating said grippers to 55 pull the upper, and additional power driven mechanism arranged for manual control to impart to the toe gripper subsequently a movement of an extent determined by the operator in a direction to change the tension 60 of the upper.

39. A machine of the class described having, in combination, a gripper for engaging an upper at the toe end of a last, means for effecting relative movement of said gripper 65 and the last to pull the upper including

yieldable connections to the toe gripper for causing the upper to be subjected to yielding tension, and means for effecting a connection with said toe gripper to control it independently of said yieldable connections.

40. A machine of the class described having, in combination, a gripper for engaging an upper at the toe end of a last, power driven means for operating said gripper to pull the upper, manual means for controlling 75 said power driven means, and means controlled by said manual means for locking said gripper against retractive movement.

41. A machine of the class described having, in combination, a gripper for engaging 80 an upper at the toe end of a last, power driven operating mechanism, and connections between said mechanism and the gripper including a clutch constructed and arranged for manual control to move said gripper 85 variable distances as determined by the operator either to pull the upper or to relax the tension.

42. A machine of the class described having, in combination, a gripper for engaging 90 an upper on a last, oppositely rotatable driving members, a driven member connected to said gripper, and means for effecting connection between said driven member and either 95 of said driving members alternatively at the will of the operator to cause the gripper to be moved either in a direction to pull the upper or in a direction to relax the tension of the upper.

43. A machine of the class described having, in combination, a toe gripper, side grippers, means for effecting relative movement of said grippers and a last to pull an upper both longitudinally and transversely, and power operated mechanism arranged for 105 manual control to permit the longitudinal and transverse tensions of the upper to be changed variably as determined by the operator.

44. A machine of the class described having, in combination, a toe gripper for pulling an upper longitudinally, side grippers for pulling the upper transversely, constantly driven power operating mechanism, and manual controlling means whereby the 110 operator may cause said mechanism to operate said grippers to tension the upper longitudinally and transversely at different respective times.

45. A machine of the class described having, in combination, a toe gripper for pulling an upper longitudinally, side grippers for pulling the upper transversely, constantly driven power operating mechanism, means for causing said mechanism to effect 120 a relative movement of the grippers and a last to pull the upper, and means for rendering said mechanism effective subsequently to vary alternately the longitudinal and the transverse tensions of the upper.

46. A machine of the class described having, in combination, grippers for engaging an upper at the toe and at opposite sides of a last, power driven means for effecting relative movement of said grippers and the last to pull the upper, additional power driven means under control of the operator for moving the toe gripper subsequently in a direction to increase the longitudinal tension 10 of the upper, and means for locking the toe

gripper to hold the upper under the increased longitudinal tension.

In testimony whereof I have signed my name to this specification in the presence of two subscribing witnesses.

JOHN T. LANCASTER.

Witnesses:

CHESTER E. ROGERS,
ABBIE L. FREAR.
